(57) **CLAIM**

We claim the ornamental design for a bottle top, as shown and described.

DESCRIPTION

FIG. 1 is a top perspective view of a bottle top, showing our new design;

FIG. 2 is a bottom perspective view thereof;

FIG. 3 is a front elevational view thereof, the rear elevational view being a mirror image thereof;

FIG. 4 is a bottom plan view thereof; and,

FIG. 5 is a top plan view thereof.
